CLAIM

I claim the ornamental design for a carrier for yoga mat and the like with hanging bag, as shown and described.

DESCRIPTION

FIG. 1 is a perspective view of a carrier for yoga mat and the like with hanging bag showing the new design; and

FIG. 2 is a perspective bottom view of the invention showing the new design; and

FIG. 3 is a left side view of the invention showing the new design; and

FIG. 4 is a front view of the invention showing the new design; and

FIG. 5 is a right side view of the invention showing the new design; and

FIG. 6 is a rear view of the invention showing the new design; and

FIG. 7 is a bottom view of the invention showing the new design; and,

FIG. 8 is a top view of the invention thereof.
